S. A. LEANE

CONTAINER FOR MATCHES

Filed May 16, 1921

INVENTOR:
Sidney Alfred Leane

By *Otto Munk*

his ATTORNEY

UNITED STATES PATENT OFFICE.

SIDNEY ALFRED LEANE, OF FARRELLS FLAT, SOUTH AUSTRALIA, AUSTRALIA.

CONTAINER FOR MATCHES.

Application filed May 16, 1921. Serial No. 470,130.

To all whom it may concern:

Be it known that I, SIDNEY ALFRED LEANE, a subject of His Majesty the King of Great Britain, citizen of the Commonwealth of Australia, residing at Farrells Flat, in the State of South Australia, in the Commonwealth of Australia, aforesaid, have invented certain new and useful Improvements in Containers for Matches, of which the following is a specification.

My invention relates to an improved container for matches, the object of the same being to provide means whereby matches which have been used can be replaced in the container without being mixed with unused matches. My device can be applied to ordinary wooden match boxes as at present in use or the invention may be constructed as an ornamental case of metal or other suitable material.

It is well known that disastrous fires have been caused through the careless throwing aside of ignited matches before they are properly extinguished. The device which I have produced provides means whereby the practice of putting the used matches into a place of safety can be easily acquired without inconvenience.

For the purposes of my invention I provide within the match box a loose or intermediate false bottom which is accommodated within the match drawer and upon which the unused matches are packed and are exposed in the ordinary way when the match box is opened.

On the underside of the match drawer and through the floor thereof I form a recess, slot, or opening of sufficient size to enable a loose match to be admitted between the said floor and the false movable bottom so that as each match is used it may be inserted in the lower part of the drawer between the bottom of the drawer and the false floor before the box is closed.

But in order that my invention may be clearly understood I will now describe the same by aid of the accompanying illustrative drawings wherein:—

Fig. 1 is a perspective view of a match box in a partially open position as viewed from the top side.

Fig. 2 is an illustration of the underside

of the drawer of the match box showing an opening at each end for the admission of used matches.

Fig. 3 is a view of the underside of the drawer showing a single opening.

Fig. 4 illustrates a portion of the match box drawer showing a modification of construction.

Fig. 5 is a sectional elevation through the match box and drawer showing false bottom.

In each of the illustrations similar letters of reference are used to denote similar or corresponding parts wherever they occur.

In the drawings *a* is the top of the outer container of the match box, *b* indicates the sides, and *c* the bottom. The sides of the sliding drawer are indicated at *d* the ends at *e*, and the ordinary bottom of the sliding drawer is shown at *f*.

Instead of the floor of the drawer extending over the whole area of the bottom it is formed with one or more openings *g* which may either extend right across the body of the drawer as indicated in Figs. 2 and 3 or the opening may consist of a relatively small hole as shown in Fig. 4 which need not necessarily be of rectangular shape but can be in the form of a circle semi-circle or other design. If the floor of the drawer is made of thin wood as is the usual custom it may be reinforced round the opening with paper or other suitable material.

The intermediate false floor or movable bottom is more clearly shown in Fig. 5 and consists of a plate of cardboard, wood, metal or other material *h* and is slightly smaller in width and length than the interior of the drawer in which it is accommodated. Before the box is filled this false floor rests upon the ordinary bottom *f* of the drawer and the matches are laid thereon in the ordinary manner, but it may be desirable to refrain from packing the box too tightly. When a match is withdrawn from the container and has been ignited, the partially consumed stub is replaced in the box by inverting the box and pushing the stub through the opening *g* in the floor of the drawer so that it is accommodated and retained between the floor of the drawer and the false bottom, each match taken from the top for use providing for its readmis-

sion on the bottom side. By this means there is great certainty that the user will see that the match is properly extinguished before it is reinserted and it will not cause 5 an unsightly litter or in any way be a source of danger as is the case with matches carelessly thrown about.

In the accompanying drawings I have shown my invention applied to wooden 10 match boxes as in ordinary use but it will of course be understood that substantially the same constructional arrangement can be applied to match boxes made of silver or other material for presentation purposes. 15 The loose plate which forms the false bottom can be used as an advertising medium if so desired.

Having now particularly described and ascertained the nature of my invention and 20 in what manner the same is to be performed I declare that what I claim is:—

1. In an improved container for matches an opening formed in the fixed floor of the match drawer said opening being of convenient size and suitably placed to permit 25 of the insertion of a partially consumed

match, and a false bottom for said drawer, substantially as described.

2. In an improved container for matches wherein an opening is formed in the fixed floor of the match drawer for the admission of a partially consumed match a movable or false bottom for the drawer of slightly less width and length than the interior of the drawer for the purpose of supporting unconsumed matches and separating them from consumed matches which are inserted through openings in the floor of the drawer substantially as described and as indicated in the drawings. 30 35

3. The herein-described improved container for matches consisting of an outer casing, a sliding drawer an intermediate or false bottom, and holes formed in the floor of the drawer said parts being arranged together substantially as described and illustrated and for the purposes set forth as a combination of parts. 40 45

In testimony whereof I have affixed my signature.

SIDNEY ALFRED LEANE.
